Primary Examiner — Elizabeth Albert*(74) Attorney, Agent, or Firm* — Altera Law Group, LLC(57) **CLAIM**

The ornamental design for a filing box, as shown and described.

DESCRIPTION

FIG. 1 is a front perspective view of a first embodiment of a filing box showing our new design;

FIG. 2 is a front elevation view of FIG. 1;

FIG. 3 is a rear elevation view of FIG. 1;

FIG. 4 is a top plan view of FIG. 1;

FIG. 5 is a bottom plan view of FIG. 1;

FIG. 6 is a side elevation view of FIG. 1, the opposite side view being a mirror image of the side shown;

FIG. 7 is a front perspective view of a second embodiment of a filing box;

FIG. 8 is a front elevation view of FIG. 7;

FIG. 9 is a rear elevation view of FIG. 7;

FIG. 10 is a top plan view of FIG. 7;

FIG. 11 is a bottom plan view of FIG. 7; and,

FIG. 12 is a side elevation view of FIG. 7, the opposite side view being a mirror image of the side shown.

The broken lines are included for the purpose of showing surfaces that form no part of the claimed design.
